UNITED STATES PATENT OFFICE.

GEORGE H. LUTZ, OF KANSAS CITY, MISSOURI, ASSIGNOR TO EQUITABLE
ASPHALT MAINTENANCE COMPANY, A CORPORATION OF MISSOURI.

PROCESS FOR SURFACING PAVEMENTS.

No. 850,382.

Specification of Letters Patent.

Patented April 16, 1907.

Application filed November 26, 1906. Serial No. 345,061.

To all whom it may concern:

Be it known that I, GEORGE H. LUTZ, a citizen of the United States, residing at Kansas City, in the county of Jackson and State 5 Missouri, have invented certain new and useful Improvements in Processes for Surfacing Pavements; and I do declare the following to be a full, clear, and exact description of the invention, such as will enable others skilled in the art to which it appertains to make and use the same.

My invention relates to a process for surfacing pavements, and is especially adaptable to pavements having a foundation of stone, brick, or like material on which it is desired to place an asphaltic or like surface, the process being more particularly adaptable for resurfacing streets which have formerly been paved with granite blocks, brick, 20 or like material.

It is the object of my invention to provide a process of applying the upper coat to the pavement so that it will adhere firmly thereto and will not slip or creep on the 25 foundation.

I have discovered that when an asphaltic or like surface is applied to the blocks or foundation when the latter is at its normal temperature the adhesion is imperfect and 30 there is a tendency of the surface to creep and "lump," making an uneven or wavy surface, but that should the blocks or foundation be heated and the outer coat be then applied a perfect adhesion is secured and a much more 35 substantial pavement formed. It is also advisable, although not indispensable, that the blocks or foundation be washed before heating in order to remove dirt and grit.

My process consists, therefore, in heating

the blocks and then applying a wash of a 40 bituminous mixture thereto while the foundation is hot and in applying a crust of a bituminous or asphaltic nature, the wash being preferably heated before its application and the crust being also hot when applied in 45 order to facilitate its working to a smooth and even surface.

This process is not only adaptable to the formation of new pavements, but is highly advantageous in resurfacing old pavements 50 of granite blocks, brick, or like material.

Having thus described my invention, what I claim as new therein, and desire to secure by Letters Patent, is—

1. The process of surfacing pavements 55 consisting of heating a base, of applying a wash of a bituminous nature thereto, and in applying a coat of thick asphalt, or like material to said base when so treated.

2. The process of surfacing pavements 60 consisting of heating a base of stone or like blocks, and applying a coat of heated asphalt thereto.

3. The process of surfacing pavements, 65 consisting of heating a solid base, applying a coat of adhesive substance thereto, and surfacing with a coat of heated asphalt or like material, for the purpose set forth.

4. A pavement comprising a base of granite or like blocks, a coat of adhesive substance covering said blocks, and a surface 70 of asphalt or like material.

In testimony whereof I affix my signature in presence of two witnesses.

GEORGE H. LUTZ.

Witnesses:

W. C. OFF,
ARTHUR L. JELLER.
